UNITED STATES PATENT OFFICE.

AXEL F. BACKLIN, OF WORCESTER, MASSACHUSETTS, ASSIGNOR TO AMERICAN STEEL & WIRE COMPANY, OF WORCESTER, MASSACHUSETTS, A CORPORATION OF NEW JERSEY.

WIRE FABRIC.

No. 868,244

Specification of Letters Patent.

Patented Oct. 15, 1907.

Application filed October 11, 1906. Serial No. 338,342.

To all whom it may concern:

Be it known that I, AXEL F. BACKLIN, of Worcester, Worcester County, Massachusetts, have invented a new and useful Wire Fabric, of which the following 5 is a full, clear, and exact description, reference being had to the accompanying drawings, forming part of this specification, in which—

Figures 1, 2 and 3 are plan views showing different forms of my improved fabric; Figs. 4 and 5 are plan 10 views showing another form of fabric with the two parts separated; Fig. 6 is a similar view showing the parts of Figs. 4 and 5 united; and Fig. 7 is a plan view of a portion of one of the fabric strips of Figs. 1 and 2.

My invention has relation to wire fabric of that class 15 which is used for the purpose of reinforcing concrete structures, such as floors, walls, roofs, etc., the object being to provide a fabric of any desired width which shall have uniform strength and appearance throughout; also to provide a fabric of this kind which can be 20 readily made upon existing machines by the addition of simple devices whereby the edges of the strips formed thereby are provided with means for securing any desired number of strips together side by side.

With these objects in view my invention consists in 25 a wire fabric composed of separate strips having their edges united in the manner hereinafter described and claimed.

Referring first to Fig. 1, the numerals 2 designate the longitudinal or strand wires of strips of woven or 30 diamond mesh wire fabric, 3 being the mesh forming wires. The strand wires 2 are omitted from the adjacent edges of the two strips to be joined, and the mesh wires 3 are formed with the bends or loops 4 at their ends. In joining the two strips the loops or bends 4 35 thereof are interlocked with each other as shown and a separate rod or strand 5 is threaded therethrough, thereby connecting the two strips by a strand or tension member 5 preferably of the same size and strength as the strand wires 2.

40 The fabric shown in Fig. 2 is similar to that shown in Fig. 1, except that the bends or loops 4^a corresponding to the bends or loops 4 of Fig. 1, instead of being interlocked with each other to receive the connecting rod of strand 5^a are placed adjacent to each other end to end to receive such rod.

In the construction shown in Fig. 3, the mesh-form-

ing wires 3 instead of being formed with spiral bends at the portions of the fabric strips which are to be united, are formed with simple bends 3^a which are hooked over the connecting rod or strand 5^b.

In the fabric shown in Figs. 4, 5 and 6, the longitudinal wire 2 of one of the two strips to be united is utilized as the coupling rod or strand, and the other strip is secured thereto by bending the ends of the meshes 3 thereover in the manner shown at 6 in Fig. 6. 50

The advantages of my invention consist in the provision of a reinforcing fabric of any desired width, built up of narrower strips, connected in such a manner that the fabric is of substantially uniform strength throughout and it will be understood that the individual strips are made up in continuous lengths from which portions of the desired or appropriate lengths may be cut to construct the final fabric, comprising a united series of narrow strips. Various other ways of connecting fabric sections may be employed within 55 the scope of my invention, since

What I claim is:

1. As a new article of manufacture, a strip of woven wire fabric made in continuous length and adapted to be cut into appropriate sizes having strand wires and web or 70 mesh wires connecting the strand wires, the web or mesh wires at at least one edge of the strip being extended beyond the last strand wire at that edge in the form of free loops; substantially as described.

2. As a new article of manufacture, a strip of woven wire fabric made in continuous length and adapted to be cut into appropriate sizes having strand wires and web or 75 mesh wires coiled about and connecting the strand wires, the web or mesh wires at at least one edge of the strip being extended beyond the last strand wire in the form of 80 V-shaped loops having bends or hooks at their apices; substantially as described.

3. As a new article of manufacture, a woven wire fabric, composed of a plurality of narrower sections of woven fabric placed edge to edge, each of said sections being 85 cut from a continuous strip and having strand wires and mesh wires, the mesh wires at each meeting edge being extended beyond the last strand wire of that section in the form of loops whose ends are formed with integral coils or bends aligned with but separable from 90 the coils or bends of the adjacent section, and a coupling rod or wire passed through the aligned eyes or coils and connecting the sections; substantially as described.

In testimony whereof, I have hereunto set my hand.

AXEL F. BACKLIN.

Witnesses:

GEORGE H. SMITH,
M. F. SHEEHAN.
